UNITED STATES PATENT OFFICE.

JAMES WELLSBY MURRAY, OF ST. GEORGE, CANADA, ASSIGNOR OF ONE-FOURTH TO SAMUEL JOHNSON, OF SAME PLACE.

WINDOW-SASH.

SPECIFICATION forming part of Letters Patent No. 643,676, dated February 20, 1900.

Application filed October 24, 1899. Serial No. 734,688. (No model.)

To all whom it may concern:

Be it known that I, JAMES WELLSBY MURRAY, a subject of Her Majesty the Queen of Great Britain, residing at St. George, county 5 of Charlotte, Province of New Brunswick, Canada, have invented certain new and useful Improvements in Window-Sashes; and I do hereby declare that the following is a full, clear, and exact description of the invention, 10 such as will enable others skilled in the art to which it appertains to make and use the same.

This invention relates to improvements in window-sashes; and its object is to provide a window-sash which can be easily and quickly 15 removed from the window-frame.

A further object is to provide a removable window-sash which is simple in construction, easily operated, and which can be manufactured at a moderate cost.

To these ends the invention consists in a 20 removable window-sash constructed substantially as herein illustrated and described, and defined in the appended claim.

Referring to the drawings, in which similar 25 letters of reference indicate similar parts, Figure 1 is a view in perspective of a window-frame provided with removable sashes constructed in accordance with this invention. Fig. 2 is a similar view showing one of the 30 sashes removed.

In the drawings, A represents a sash-frame of any usual or preferred form, which may be constructed of wood or metal.

The window-sashes are constructed of a 35 sheath B, in which the sash B' is slidably mounted, and so constructed as to permit the ready removal therefrom of the sash B'. The sheath B is constructed, preferably, of wood, though it may be formed of metal, and com- 40 prises the cross-bar b and the depending arms or sides b', which are provided with grooves b² in their inner faces of a width sufficient to receive the sides of the sash B. If preferred, the sides of the sash B and also the bottom

45 thereof, as well as the lower ends of the arms b', may be suitably mortised or cut away to provide a close fit and give the sash and its sheath the appearance of an ordinary sash

when in their normal position, as is clearly shown in the drawings. 50

It will be obvious from the above description that the sash B' is adapted to slide freely in the grooves b² of the sheath B and may be readily removed entirely therefrom when desired. 55

The sash B' is provided at a suitable point with a pivoted latch b³, which is adapted to engage a suitable pin b⁴, secured on the sheath B, by means of which the sash may be securely locked to the sheath when they are in 60 their normal closed position. (Shown in Fig. 1.)

The sheath B is provided with a pivoted catch b⁵, which is adapted to engage an orifice in the window-frame to retain the sheath and 65 sash in their proper position in the frame. It will be understood, however, that instead of this device for retaining the sash in its position in the frame the usual cord and weight may be used, if preferred. 70

When it is desired to remove a sash for any purpose, as for washing, repairing, &c., it is only necessary to raise the sheath to the top of the frame and disengage the latch b³, whereupon the sash may be readily withdrawn from 75 the sheath and after having been washed or repaired returned to its former position.

It will be obvious that instead of constructing the sheath so that the sash can be removed from the bottom thereof it may be constructed so as to permit the sash to be removed from the top. 80

An important advantage in addition to those above mentioned incident to this invention is that the ordinary glass sash may be 85 quickly and easily replaced by a sash having a wire screen.

The operation of this invention and its many advantages are believed to be sufficiently obvious in view of the above description and necessitates no further detailed explanation. 90

While I have herein shown a preferred form of carrying my invention into effect, yet I do not desire to limit myself to such preferred 95 details of construction, but claim the right to

use any and all modifications thereof which will serve to carry into effect the objects to be attained by this invention in so far as such modifications and changes may fall within the 5 spirit and scope of my said invention.

I claim—

A window-sash, comprising a sheath adapted to fit in a window-frame and having an open side, grooves formed in said sheath adjacent to said open side; a pin fixed to the side of said sheath, a sash mounted to slide in said grooves and adapted to be removed from and

inserted in said open side; and a latch pivoted to said sash and adapted to engage the pin of said sheath, whereby the sash may be 15 locked to said sheath, substantially as described.

In witness whereof I have hereunto set my hand in the presence of two witnesses.

JAMES WELLSBY MURRAY.
